(57) **CLAIM**

The ornamental design for a pet toy, as shown and described.

DESCRIPTION

FIG. 1 is a front perspective view of the pet toy;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof;

FIG. 9 is an exploded perspective view thereof; and,

FIG. 10 is an environmental view thereof.

The broken lines illustrate environment and portions of the pet toy that form no part of the claimed design.

1 Claim, 10 Drawing Sheets
